UNITED STATES PATENT OFFICE.

GEORGE F. ANDERSON, OF OKLAHOMA CITY, OKLAHOMA.

DISPENSING ATTACHMENT FOR BOTTLES.

Application filed April 17, 1922. Serial No. 553,660.

To all whom it may concern:

Be it known that GEORGE F. ANDERSON, a citizen of the United States of America, residing at Oklahoma City, in the county of 5 Oklahoma and State of Oklahoma, has invented new and useful Improvements in Dispensing Attachments for Bottles, of which the following is a specification.

The object of the invention is to provide 10 a dispensing device in the form of an attachment for use in connection with bottles, demijohns, carboys and the like to avoid the necessity of maintaining the receptacle in a normally upright position and manu- 15 ally tilting the same in order to discharge a portion of the contents thereof; and furthermore to provide a device of this type which can readily be applied to and detached from bottles as they are required for use while 20 leaving the receptacle unequipped during shipment or storage or when not in use, so that the possibility of injury to the dispensing attachment is minimized; and with these 25 objects in view the invention consists in a construction and combination of parts of which a preferred embodiment is shown in the accompanying drawings, wherein:—

Figure 1 is a side view of a dispensing device or attachment applied in the operative 30 position to a bottle.

Figure 2 is a front view of the same.

Figure 3 is a bottom plan view thereof.

The device consists essentially of a cap or cup 10 designed to receive the neck of a bottle 11 and snugly fit the latter, so that the free edge may bear against the shoulder of the bottle, not tight enough, however, to preclude the entrance of air which is necessary for the venting of the device. The cap 15 is provided with a discharge faucet 12 of any suitable valved type of which a conventional form is indicated in the drawing. When the bottle is placed in the cap, the 20 contents will flow through the neck of the former until it has filled the cap to the level

of the mouth of the neck. Thus, when the faucet is opened, the contents may readily flow through the faucet from the cap, being replaced in the latter by transfer from the bottle. The cap is pivotally mounted in a 50 bracket 14 adapted to be attached to the bottle in order to hold the cap or cup in proper position with relation to the bottle.

In the construction illustrated the bracket is provided with an arm 15 extending longitudinally of the bottle and having pivotally mounted on its free end as indicated at 16 a clamping ring 17 to encircle or embrace the bottle near the bottom. To permit of pivotal movement of the cap or cup obviously the retaining ring may be disengaged from the bottle or may be slid longitudinally thereof, and the attachment is preferably applied to the bottle when the latter is in an upright or normal position with the cap inverted so 60 as to be fitted down over the neck of the bottle. This arrangement having been effected and the bracket secured by the clamping ring to the bottle, the latter may be inverted to the position indicated in the drawings so 65 as to provide for the dispensing of the liquid from time to time as may be required through the outlet afforded by the faucet.

Having described the invention, what is claimed as new and useful is:—

A dispensing attachment for bottles comprising a bracket designed for mounting on a wall or partition, a cap pivotally mounted in the bracket for the reception of the neck of the bottle, the cap supporting the weight 80 of the bottle and being provided with a dispensing faucet, and an arm carried by the bracket and extending longitudinally of the attached bottle, said arm being provided with means for slidable engagement with the 85 bottle to preclude swinging movement of the bottle on the pivotal connection of the cap.

In testimony whereof he affixes his signature.

GEORGE F. ANDERSON.
